UNITED STATES PATENT OFFICE.

JOHN H. KILLION, OF CHICAGO, ILLINOIS.

BARREL OR BOX.

1,011,249.

Specification of Letters Patent. Patented Dec. 12, 1911.

Application filed January 9, 1907. Serial No. 351,437.

To all whom it may concern:

Be it known that I, JOHN H. KILLION, a citizen of the United States, residing at Chicago, in the county of Cook and State of Illinois, have invented certain new and useful Improvements in Barrels or Boxes, of which the following is a full, clear, and exact specification.

This invention relates to barrels, boxes or other like receptacles for packing, storing and shipping purposes and it has for its primary object to provide an improved form of barrel, box or the like, which shall be of knocked-down construction and will be light and durable when in condition for use and compact when in its knocked-down form.

Another object of the invention is to provide an improved form of barrel or box of this type which shall have flexible dimensions or be capable, at the will of the user, of being reduced in size without necessarily using substitute parts.

With a view to the attainment of these ends and the accomplishment of certain other objects, which will hereinafter appear, the invention consists in the features of novelty which will now be described with reference to the accompanying drawings and more particularly pointed out in the claims.

Figure 1 is a side elevation, partly in vertical section, of a form of barrel, cask or box embodying this invention. Fig. 2 is a cross section thereof on the line 5—5 of Fig. 1. Fig. 3 is a front view partly in vertical section, showing the parts in the position they assume when reduced to a half-high barrel or box. Fig. 4 is an enlarged detail view of the hoop or band employed showing the locking devices. Fig. 5 is an enlarged detail view of the inner shell in horizontal section, illustrating the joint. Fig. 6 is a side elevation, partly in vertical section, of another form of barrel, cask or box, embodying this invention. Fig. 7 is a plan section thereof on the line 10—10 of Fig. 6. Fig.

8 is a side elevation, partly in vertical section, showing the members telescoped and arranged to produce a half-high barrel. Fig. 9 is a side elevation, partly in vertical section, of another form of barrel, box or cask embodying this invention. Fig. 10 is a horizontal section thereof on line 13—13 of Fig. 9. Fig. 11 is a side elevation, partly in vertical section, showing the parts telescoped to produce a half-high barrel. Fig. 12 is a side elevation, partly in vertical section, of

another form of barrel, cask or box embodying this invention. Fig. 13 is a horizontal section thereof on the line 16—16 of Fig. 12. Fig. 14 is a side elevation, partly in vertical section, of the parts telescoped to produce a half-high barrel. Fig. 15 is an enlarged detail view of the joint of the hoop showing the same in horizontal section, and Fig. 16 is a vertical sectional view of a head for any of the forms of the barrels or receptacles before referred to, composed of sheet metal or material.

Referring now more particularly to Figs. 1 to 3 of the drawings, it will be seen that the barrel or receptacle comprises two heads 1, 2 and a body portion consisting of a double shell, the outer part of which is corrugated and both wall parts composed of sheet material, such as sheet steel or the sheet metal commercially known as tin. The edges of these wall parts where they come together are provided with interlocking joints, better shown in transverse section in Fig. 2. The heads 1 and 2 are provided with grooves and shoulders adapted to engage with the walls. With a barrel or receptacle thus constructed, it will be seen that the joints make it substantially tight and suitable for storing or shipping finely divided materials, such as flour, cement, et cetera. The longitudinal joints also add strength and durability to the body of the barrel for resisting longitudinal strains or those strains tending to crush in the heads. The corrugations of the outer shell are fully adequate to resist all ordinary strains to which an article of this character is apt to be subjected.

The structure, in addition to being light and durable, is economical of manufacture and susceptible of being returned or shipped back to the original consignor in a knocked-down and compact form. The wire hoops, being a commercial product readily obtained, may be discarded when removed and the other elements of the barrel or a plurality of such barrels nested together in a compact form for shipping and the bulk thereby very materially reduced.

In the form of the invention shown in Figs. 1 to 3 inclusive, the construction is susceptible of being reduced to a half-high barrel by telescoping the parts, thus making it possible for the consignee to ship back to the consigner a half-barrel of goods in the same barrel, with its bulk reduced one-half and thereby effect a considerable sav-

ing in the cost of expressage or freight, while placing the original consignor again in possession of all of the component parts of the full-sized barrel in readiness for repeated use. In carrying this feature of the invention into effect, the barrel is divided horizontally into two sections and is provided with means at the junction of the two sections for securing them together. It is immaterial, so far as this feature of the invention is concerned, whether each section be of a single thickness or of a double wall or shell. It is illustrated, however, as being composed of an outer corrugated shell and an inner plain shell. The heads 1, 2, of this form are also provided with means for attachment to the shell or body of the barrel but in this form it is important that the attaching means of the head and the shell be of such a character that the upper head will be capable of forming a proper joint with the upper end of the lower section when the parts are telescoped together to produce a half-high barrel. To that end, therefore, the upper and lower sections of the barrel are made inter-changeable with the heads, the lower section 14 of the inner shell being provided at its lower end with a U-shaped return bend constituting a shoulder 15 and a flange 16, and at its upper end with a fac simile return bend constituting a shoulder 17 and a flange 18, and the upper section 19 of the inner shell being formed at its upper and lower ends respectively with return bends 16, 17 the same in form and dimensions as the return bends of the lower section, constituting shoulders 20, 21 and flanges 22, 23. The edges of the heads 1, 2, are provided with peripheral grooves 24, 25, which receive the inturned flanges of the shell sections 14, 19 at the upper and lower ends of the barrel when these sections are stacked one upon the other in the position shown in Fig. 3 and when in this position the flanges 18, 22 rest one upon the other, while the flanges 16, 23 take into the grooves 24, 25 to prevent the heads from pulling out. The sections 14, 19 are firmly secured together at their adjoining edges by a hoop or band 26, which is of U-shaped or channel-bar formation in cross section, so as to be complementary in shape to the pair of return bends at the adjoining ends of the shell sections 14, 19, the horizontal flanges of the band or hoop 26 embracing and snugly fitting against the shoulders 17, 20 of the contiguous return bends. After the band or hoop 26 has been thus placed, its ends may be drawn together and secured one to the other by any suitable means such as an interlock comprising a loop 27 struck out from one end and passing through a registering aperture in the other end, the loop being held against withdrawal by a cotter-pin or key 28. With the device thus constructed, the receptacle is

complete but unless made of very stout material would not possess sufficient strength for many purposes to resist lateral strains. For ordinary usage, therefore, the plain inner shells 14, 19, serve as a lining, constituting a tight closure for finely divided materials in addition to affording adequate means of connecting the upper and lower sections of the barrel together and securing the heads in place, the edges of each of the plain sections 14, 19 being provided with the joint 5, as shown in Fig 2, but owing to the presence of the return bends at the upper and lower ends of the sections 14, 19, the joint should be formed as shown in Fig. 5, the flanges 18, 22 and the shoulders 17, 20 being cut away as indicated at 29 owing to the practical impossibility of folding the metal back and forth upon itself to produce this joint 5 where the return bends at the upper and lower ends of the shell sections occur. In order, therefore, that the structure may be rendered sufficiently rigid to resist strains in all directions each of the upper and lower sections 14, 19 is provided with an outer shell of corrugated metal or material, the upper outer shell being indicated at 30 and the lower one at 31 and the corrugations are shown as extending longitudinally of the barrel with the sections 30, 31 fitting between the shoulders 20, 21 and 15 15, 17 respectively. These corrugated sections 30, 31, are also in the form of bands or strips with their ends overlapped and the corrugations interlocked or meshed, as shown in Fig. 2. Where the overlap occurs the ends may be secured together by any suitable means, preferably means similar to that described with reference to the hoop 26 consisting of loops 32, 33 at the inner and outer ends respectively passing through registering apertures and held against withdrawal by keys or cotters 34. By thus encircling the sections 14, 19 with the corrugated sections, it will also be seen that the inner sections of the shell are held snugly in place against the heads and prevented from expanding.

In Fig. 3 the construction last described is shown in the form of a half-high barrel with the half-high sections telescoped one within the other. In thus re-arranging the elements for the purpose of making a half-barrel the corrugated parts 30 and 31 may be loosened or removed, by first withdrawing the cotters 34. The upper head, together with the upper inner section 19 and upper outer section 30 are lowered into the position shown in Fig. 3 until the return bend at the lower end of the upper section 19 embraces the flange of the head 2, which is formed by the groove 25, the lower section 14 being first removed and then wrapped around the section 19 so as to nest or telescope therewith, the flexibility of the

metal or material of which these sections are composed being sufficient to permit the parts to be thus inserted one within the other; and the groove 25 in the lower head 5 and 24 in the upper head being of sufficient width to receive the flanges 20, 23 when doubled as in the telescoped condition. This telescoped condition of the members will of course require more or less expansion of 10 the outer section 14, or more or less contraction of the inner section 19 but this is amply taken care of in the looseness of fit of the loops 32, 33 in the corrugated sections and the joint 5 in the plain sections. 15 To permit the corrugations to lie together closely where the loops 32, 33 occur, the cotters 34 may first be removed, and reinserted through both sets of loops, after the loops on the inner shell 31 have entered those in the 20 outer shell 30. In this case the cotters in one shell only would be used in the half high barrel. In the half high barrel two of the four cotters would in that case be unused. Both the looseness of the fit and the thin 25 and flexible nature of the sheets facilitate the assembling of the parts as above described. The hoop 26, which is no longer needed while the barrel is in its telescoped or half-high condition, may be disposed of by being placed within the barrel at the bottom, as shown in Fig. 3, the cotter 28 at that time being of course, removed to allow the 30 hoop to be contracted.

In the form of the invention shown in 35 Figs. 6 to 8 inclusive, which is also capable of being converted into a half-high barrel or box, by telescoping the elements substantially as before described with reference to Figs. 1 to 5, the inner plain sections 40 35, 36 are attached to the heads 1, 2, by means of wire hoops or bands 37, 38 respectively, which engage in grooves formed in the upper and lower ends of the sections 35, 36 by producing peripheral corrugations therein resulting in a shoulder 39 45 and a flange or hook 40 on the upper end of the upper section, and a similar shoulder 41 and flange or hook 42 on the lower end of the lower section and which wires 37, 50 38 press these hooks 40, 42, into peripheral grooves 43 of complementary shape in heads 11. The lower end of the upper section 35 and the upper end of the lower section 36 are provided with fac-simile shoulders and 55 hooks so that the heads will be inter-changeable with the ends of either section. This shoulder of the upper section is shown at 44 and the hook at 45, while the shoulder of the lower section is shown at 46 and the hook at 47. These return bends or corrugations at the contiguous ends of the sections made for the production of the said hooks and shoulders, are capable of being interlocked or hooked together; as shown in Fig. 6, so that when the ends of the sections are

thus locked together or otherwise secured, the sections will be prevented from pulling apart and a sufficiently tight joint will be formed where they come together. Where the receptacle is provided with the outer 70 corrugated shells 30, 31, as before described with reference to Fig. 1, these will hold the inner shells or lining 35, 36, against expansion and constitute an effective means of retaining the joint 5 in position; consequently the device may be complete without other aid for re-inforcing the joint at the middle but if desired, this joint may be made doubly secure by providing it with the hoop 26 before described with reference to Fig. 1, 80 and which, as will be understood, is inserted over the shoulders 44, 46 between the ends of the corrugated sections 30, 31. When the barrel or receptacle of this construction is to be telescoped to make a half-high barrel the 85 parts are disposed as shown in Fig. 8, the two inner sections 35 and 36 being nested or telescoped with their flanged ends engaging the grooves 43 and held in place by the wires 37, 38 before described, the arrangement and 90 construction being otherwise the same as that shown in Figs. 1 to 5.

In the form of the invention shown in 95 Figs. 9 to 11 inclusive, the corrugations of the body portion run horizontally or transversely of the barrel. In this form the inner shell or lining is omitted and the upper corrugated section 48 is supported directly upon the lower corrugated section 49 when a barrel of full height is to be produced. The outer extremities of the two sections are secured to their respective heads 1, 2 by any suitable means, the employment of the wire hoops or bands 37, 38 100 pressing the end corrugations into corresponding grooves in the heads, being a convenient method. When in this position the contiguous ends of the sections are bonded together by a band or flanged hoop 50 similar in construction to the hoop 26 before 105 described, excepting that it should be of the proper dimensions for embracing the outer bends of the two corrugations contiguous to the meeting ends of the sections, the extremities of the hoop or band 50 being 110 secured together by loop 27 and pin 28 before described. When a barrel of this construction is to be telescoped for making a 115 half-high barrel the sections 48, 49 are simply nested one within the other as shown 120 in Fig. 14 and the band 50 may be conveniently placed inside to preserve it.

In the form shown in Figs. 12 to 15, the 125 construction possesses a greater degree of variation in the dimensions of the receptacle than any of the other forms. In this form the corrugations of the upper and lower sections 48, 49 also run horizontally but instead of being supported one upon the other, as in Fig. 9, the sections are tele-

scoped so that their corrugations inter-mesh or inter-lock, this not only constituting a means of connecting the sections together at their contiguous ends but making it possible to vary the height of the barrel or receptacle throughout a wide range, from a full-high barrel to one of half-height, depending only upon the extent to which one of the sections is to be inserted within the other. This method of connecting the sections together makes it desirable, however, to brace or re-inforce them from the inside to prevent the overlapped ends of each section from squeezing together or contracting in a direction transverse to the longitudinal axis of the barrel. For this purpose an internal hoop 51 is employed. This hoop is of substantially the same construction as the hoop 50, excepting that its flanges 52 are turned outwardly so as to embrace the corrugations on the inside. Ordinarily it would be placed at about mid-length of the barrel and directly opposite, but on the outside should be arranged one or more bands 25 or wire hoops 53, one of these being at the extremity of the outside section so as to hold said extremity in place and prevent both sections from expanding at the mid-length of the barrel. The ends of this internal hoop 51 need not be secured against expansion inasmuch as that result is prevented by the bands or wires 53 but it is desirable that contraction be guarded against and this may be accomplished by jointing 35 the ends in the manner shown in Figs. 13 and 15, the flanges 52 being omitted where the joints occur and the joint being formed by folding the metal back and forth upon itself to produce a socket 54, in which the 40 opposite extremity of the hoop is inserted.

In Fig. 16 is shown a head composed of corrugated sheet metal which may be employed as a substitute for the heads of any form of the barrel or cask. The top or 45 body of the head may be corrugated to give the requisite stiffness while its edges are flanged as shown at 54 to produce the groove and flanges of the proper shape and dimensions that may be required for any particular form of body to be used in combination therewith.

In order that the invention might be fully understood by those skilled in the art, the details of the foregoing embodiments there- 55 of have been thus specifically described but—

What I claim as new therein and desire to secure by Letters Patent is—

1. In a barrel or receptacle, the combination with a corrugated body composed of a 60 plurality of independent strips of corrugated material, each having its ends detachably conjoined to form a body element, means for detachably securing said body elements together, and a head detachably secured in 65 the end of the body.

2. In a barrel or receptacle, the combination of a plurality of body elements, inherent means for securing said body elements together end to end, one of such body elements being composed of a continuous strip 70 with its ends overlapped and detachably connected together whereby its diameter may be reduced when such ends are detached and inserted within the other body elements making a reduced capacity, and a head detachably secured in one of said body elements. 75

3. In a barrel or receptacle, the combination of a plurality of body elements, each composed of a continuous corrugated strip 80 having its end overlapped and detachably secured together, means for securing said body elements together end to end, and a head detachably secured in one of said body elements. 85

4. In a multiple capacity and knockdown barrel or receptacle, the combination of a plurality of body elements, each including a single strip of material forming the inner wall or lining and each having shoulders 90 at the ends thereof, said elements being arranged end to end, a single piece external band or hoop having flanges embracing said shoulders, and detachable heads in said body elements. 95

5. In a barrel or receptacle, the combination of a body element forming the inner wall or lining, having shoulders at both ends, a corrugated body element surrounding the first said body element and extending between said shoulders, and a head arranged in operative relation to the first said body element. 100

6. In a barrel or receptacle, a body composed of a plurality of interchangeable sections detachably joined end to end and adapted to be assembled in a telescoped condition with heads in place making a receptacle of reduced capacity, each section comprising an inner strip of smooth material 110 and an outer strip of corrugated material. 110

7. In a multiple capacity barrel or receptacle, a body composed of a plurality of telescopic sections, each section comprising an inner strip of smooth material, and an outer strip having a form adapted to support and protect said inner strip all of said strips being detachable. 115

8. In a barrel or receptacle, a body composed of a plurality of interlocking sections, 120 each section comprising an outer strip of corrugated sheet material, and an inner strip of smooth material all said strips being detachable.

9. A device of the class described, comprising two body sections, an upper and a lower, each consisting of two cylindrical sheet metal walls, the inner smooth and the other corrugated, two heads each having a peripheral flange and groove for engage- 125 130

ment of the outer ends of the wall sections, one intermediate peripheral inturned channel hoop to connect the intermediate ends of the wall sections with means for attaching the several parts securely together either in an extended or telescoped position.

10. A multiple capacity and knockdown barrel consisting of the following parts in combination, namely—first, a plurality of 10 telescopic wall sections each comprising a smooth inner wall having its meeting edges loosely joined by a compression resisting thrust joint and having its end edges turned outward and then inward forming 15 shoulders and clamping grooves, and a corrugated outer wall held between the said shoulders and having its meeting edges detachably locked together; second, one or 20 more hoops each having means for detachably locking its ends together, and having inturned flanges to bind together the abutting shoulders of adjacent wall sections; and third, two heads each having a peripheral groove to engage the shoulder and 25 flange of the adjacent wall section.

11. A multiple capacity barrel consisting of two heads, a plurality of wall sections each comprising an inner wall having its meeting edges detachably connected by a 20 compression resisting joint, and an outer wall having its meeting edges detachably connected by a tension and compression resisting joint.

12. In a multiple capacity barrel, a plurality of wall sections, the longitudinal edges of which with respect to the axis are detachably joined together either singly or

in multiple by means of cotter pins engaging with loops, and slots integral with the plates.

13. In a device of the class described, a plurality of mutable sections, all of which are alike and interchangeable, each having two end flanges turned outwardly and then inwardly and adapted to engage with heads suitably formed therefor, means of the nature of a hoop adapted to engage adjacent end flanges aforesaid when sections are placed end to end and hold them securely together, and means for opening and closing said sections at the side with means for locking when closed.

14. In a device of the class described, a plurality of like sections each composed of a lining element having its edges detachable on one side and end flanges adapted to engage with a head on one end and with another section on the other end and an outer shell adapted to inclose said lining between said flanges and hold the lining edges in engagement and having means to lock together 60 its own detachable edges, a pair of heads, and a hoop with flanges adapted to lock with adjacent section flanges and hold two sections together, said hoop having means to open and to lock when closed.

In testimony whereof I have signed my name to this specification, in the presence of two subscribing witnesses, on this 4th day of January A. D. 1907.

JOHN H. KILLION.
